FUSE BLOCK

Magnus G. Dahl, West Hartford, Conn., assignor
to The Arrow-Hart & Hegeman Electric Com-
pany, Hartford, Conn., a corporation of Con-
necticut

Application June 15, 1935, Serial No. 26,818

7 Claims. (Cl. 200—133)

This invention relates to fuse blocks. More particularly it relates to fuse blocks for fuses of the screw plug type.

- In many instances fuse blocks are used in which fuses of opposite polarity are located next to each other. It is desirable under such conditions that the receptacles or sockets or screw shells of the fuses be separated from each other by a positive insulating medium.
- 10 It is an object of my invention to provide a positive insulating medium between adjacent screw plug type of fuse receptacles.

Under some conditions it is not necessary for a positive insulating medium or body to be placed 15 between fuses mounted upon the same fuse block.

It is an object of my invention to provide a removable fuse separating barrier adapted to be positioned between fuse receptacles or not, so that the same block may be used either when 20 adjacent fuses are to be of opposite polarity, or when adjacent fuses need not be separated by a positive insulating medium.

A further object of my invention is to provide a removable barrier on the fuse block between 25 the fuse receptacles, which barrier will be held in position by the screw shells of the fuse receptacles and also, indirectly, by the same means which hold the fuse receptacles to the fuse block.

Other objects and advantages of my invention 30 will become apparent as it is described in connection with the accompanying drawing.

In the drawing:—

Figure 1 is a plan view of my invention.

Figure 2 is a longitudinal vertical section view 35 taken on line 2—2 of Figure 1.

Figure 3 is a longitudinal vertical section view taken on line 3—3 of Figure 1.

Figure 4 is a transverse section view of my invention, taken on line 4—4 of Figure 1.

40 Referring to the drawing it will be noted that the fuse block or base 10 is formed of insulating material. Customarily such fuse blocks are made of porcelain but, obviously other insulating materials may be used. The fuse block may be 45 rectangular in shape with rounded corners and with side walls perpendicular to the face of the block. The block may be hollowed out from the bottom to form a large recess. At opposite sides of the block on its top face are seated conventional screw shells or fuse receptacles 12 and 14 into which may be screwed conventional screw type plug fuses. Each of the fuse receptacles 12 and 14 has in its side wall adjacent the bottom of the receptacle an aperture (see 12a) facing toward one end of the block and receiving a wire

terminal plate. These terminal plates 16 and 18 are identical and may be stamped from sheet metal. Each plate has a portion lying outside of the receptacle and a portion within the receptacles lying upon the bottom thereof. Referring to the plate 16 there is provided in the inside portion a large round aperture 20 through which the shank of a screw 22 passes freely so that there is no electrical connection therebetween. Still referring to terminal plate 16, an insulating disc or washer 24 lies on said plate so as to insulate it from the head of the screw 22. In order that the screw shell 12 shall not have a direct electrical connection with the screw 22 there is provided in the center of the bottom of the shell 12 an aperture through which the shank of the screw passes, the aperture being larger than the shank of the screw so that the screw will be out of electrical contact with the shell. Thus the head of this screw 22 affords a central contact 10 for the fuse receptacle 12, and may be engaged by the center contact of a fuse plug as the fuse plug is screwed into the shell 12. Preferably the bottom of the screw shell around the edge of the aperture is extruded upwardly.

20 The portions of the wire terminals 16 and 18 which extend outside of the fuse receptacles may each have an aperture formed in it with the metal around the aperture extruded and screw threaded for the reception of wire terminal screws 26, 28. 30 The extruded portion may extend down into a recess in the top of the base or block and thus assist in holding the terminal in position.

Within the recess of the fuse block or base 10 there is provided a double pole switch mechanism, comprising two pairs of stationary contacts 30, 32 and 34, 36, each pair being bridged by a movable contact 38, 40 which is mounted upon an insulating plate 42 that is rectilinearly movable between the adjacent surfaces of each pair 40 of stationary contacts by a handle (not shown) in a plane parallel to the top of the fuse block or base. One of the stationary contacts 30 may be secured in position by and electrically connected with the central screw 22. The switch mechanism per se forms no part of this invention and therefore need not be described in detail.

In the embodiment of the invention which I have shown there are provided two fuse receptacles and two sets of stationary switch contacts so that the device forms what is commonly known as a double pole construction. Thus the two fuse receptacles will be required to carry current of opposite polarity. Thus it is desirable 55

to provide positive insulating means between the shells of the two receptacles.

For this purpose I provide a barrier 44 of suitable insulating material positioned between the fuse receptacle 12 and 14, and I provide in the upper face of the insulating fuse block a shallow well 45 into which the bottom portion of the barrier fits. The bottom portion of the barrier 44 has straight end walls 44a parallel to the ends of and perpendicular to the surface of the block. The side walls 44s, also, of the bottom portions of the barrier are perpendicular to the surface of the block but are arcuate. The centers of the arcs lie in the central axes of the fuse receptacles 12 and 14. However the radius of curvature of these arcs or curved walls is less than the radius of curvature of the fuse receptacles, so that the curved walls of the bottom of the barrier lie under the bottoms of the fuse receptacles.

The upper portion of the barrier 44 has plane end walls in extension of the walls 44a of the bottom. The side walls 44x of the upper part of the barrier are curved, the radius of curvature of these walls being slightly greater than the radius of curvature of the fuse receptacle. The centers of the arc of curvature lie in the axes of the fuse receptacles when those receptacles are situated in assembled position.

Thus shoulders 44z are provided at each side of the barrier which shoulders underlie the fuse receptacles 12 and 14 respectively. Thus it will appear that as the device is assembled, the barrier will be placed within the well and then the fuse receptacles 12 and 14 will be screwed in position, with the end portions of their bottom bases overlying the shoulders of the barrier and thus holding the barrier securely in position.

It is an advantage to have the barrier removable from the base for the reason that the barrier need not be used when conditions do not require it, such as when the base is to be used in constructions which do not have fuses of opposite polarity upon it. Also it is an advantage not to have to mold the barrier and the fuse base as one piece. It is an added advantage to be able to mold a uniform base which is adapted for use under varying conditions and to mold separately an insulating barrier which may be used in connection with the base whenever conditions require it.

Many changes in form within the scope of my invention will occur to those skilled in the art. I therefore do not limit myself to the specific form of the embodiment shown.

55 I claim:—

1. In combination, a base of insulating material, a pair of screw shell fuse receptacles, means to secure said receptacles on said base, said base having a well between said receptacles, a barrier formed separately from the base and seated in said well, said barrier having portions underlying said receptacles to retain said barrier irremovably in place. 5

2. In combination, a base of insulating material, a pair of screw shell fuse receptacles, means to secure said receptacles on said base, said base having a well between said receptacles, a barrier formed separately from the base and having an enlarged integral base portion seated in said well, said base portion underlying said receptacles 15 whereby the barrier is held in place.

3. In combination, a base of insulating material, a pair of screw shell fuse receptacle contacts, means to secure said receptacle contacts on said base, and a barrier formed separately 20 from said base and seated thereon between said receptacle contacts, said barrier having portions underlying said receptacle contacts whereby the barrier is held in place.

4. In combination, a base of insulating material, a pair of screw shell fuse receptacle contacts, means to secure said receptacle contacts on said base, and a barrier formed separately 25 from said base and seated thereon between said receptacle contacts, said barrier being engaged 30 and held in position by said receptacle contacts.

5. In combination, a base of insulating material, a pair of screw shell fuse receptacles, a barrier formed separately from said base and positioned between said receptacles, and central 35 conducting means within said receptacles and insulated therefrom securing said receptacles and said barrier irremovably upon said base.

6. In combination, a base of insulating material, a pair of screw shell fuse receptacles, a barrier formed separately from said base and positioned between said receptacles and having portions underlying said receptacles, and common 40 means to secure said receptacles and said barrier irremovably upon said base. 45

7. In combination, a base of insulating material, a pair of screw shell fuse receptacles, a barrier formed separately from said base and positioned between said receptacles and having portions underlying said receptacles, and central 50 conducting means within said receptacles and insulated therefrom securing said receptacles and said barrier irremovably upon said base. 55
